(57) **CLAIM**

The ornamental design for a flask for perfumery products, as shown and described.

DESCRIPTION

FIG. 1 is a perspective view taken from the front and top of a flask for perfumery products showing the present design. FIG. 2 a perspective view taken from the front and bottom of the flask for perfumery products of FIG. 1.

FIG. 3 is a front elevation view of the flask for perfumery products of FIG. 1.

FIG. 4 is a front elevation view of the flask for perfumery products of FIG. 1, shown with its cap in an alternate, lowered position concealing the neck and exposing the nozzle; and wherein the concealed neck portions are upwardly displaced.

FIG. 5 is a top plan view of the flask for perfumery products of FIG. 1.

FIG. 6 is a bottom plan view of the flask for perfumery products of FIG. 1; and,

FIG. 7 is an exploded perspective view from the front and bottom of the flask of FIG. 1, with the inner chamber and the spray nozzle removed from an outer chamber.

1 Claim, 6 Drawing Sheets
